CLAIM

The ornamental design for a plumbing fitting, as shown and described.

DESCRIPTION

Notice: More than one reissue application has been filed for the reissue of Pat. No. D617,424. Application Ser. No. 29/476,353, filed Dec. 12, 2013, is a reissue divisional of application Ser. No. 29/424,137 (the present application), filed Jun. 7, 2012, which is an application for reissue of U.S. Pat. No. D617,424.

FIG. 1 is a right, top, front perspective view of a plumbing fitting according to my new design;

FIG. 2 is a right side elevational view thereof, the left side elevational view thereof being a mirror image of the right side shown;

FIG. 3 is a front elevational view thereof;

FIG. 4 is a rear elevational view thereof;

FIG. 5 is a top plan view thereof; [and.]

FIG. 6 is a bottom plan view thereof[.];

FIG. 7 is a right, top, front perspective view of a plumbing fitting according to another embodiment of my new design; FIG. 8 is a right side elevational view thereof, the left side elevational view thereof being a mirror image of the right side shown;

FIG. 9 is a front elevational view thereof;

FIG. 10 is a rear elevational view thereof;

FIG. 11 is a top plan view thereof; and,

FIG. 12 is a bottom plan view thereof.

[The broken line representations in the figures are for the purpose of illustration only, and form no part of the claimed design.]

The broken lines depict portions of the plumbing fitting in which the design is embodied that are not considered part of the claimed design.

In a preferred embodiment, the nature of this product is a plumbing fitting, such as a faucet control for a shower and/or bath.

1 Claim, 4 Drawing Sheets

Matter enclosed in heavy brackets [ ] appears in the original patent but forms no part of this reissue; matter printed in italics indicates the additions made by reissue.
